CLAIM

The ornamental design for a heat deflector for fire pit as shown and described.

DESCRIPTION

FIG. 1 is an upper perspective view of a heat deflector for fire pit showing my new design.

FIG. 2 is a front elevation view thereof.

FIG. 3 is a right side elevation view thereof.

FIG. 4 is a rear elevation view thereof.

FIG. 5 is a left side elevation view thereof.

FIG. 6 is a top plan view thereof; and,

FIG. 7 is a bottom plan view thereof.

The dashed lines shown in the drawings are for purposes of illustrating portions of the heat deflector for fire pit that form no part of the claimed design.
